DESIGN FOR A SWEATER

Abraham Naidish, New York, N. Y.

Application December 5, 1945, Serial No. 124,384

Term of patent 3½ years

(Cl. D3—4)

To all whom it may concern:

Be it known that I, Abraham Naidish, a citizen of the United States of America, residing in New York city, county of Kings, and State of New York, have invented a new, original, and ornamental Design for a Sweater, of which the following is a specification, reference being had to the accompanying drawing, forming part thereof, wherein,

The figure is a front view of a sweater showing my new design.

The rear of the sweater is identical in appearance with the front shown.

I claim:

The ornamental design for a sweater, substantially as shown and described.

ABRAHAM NAIDISH.
